(57) **CLAIM**

The ornamental design for a media storage container with individual storage trays, as shown and described.

DESCRIPTION

FIG. 1 is a perspective view of a media storage container with individual storage trays, showing our new design; FIG. 2 is a top plan view of the media storage container of FIG. 1;

FIG. 3 is a bottom plan view of FIG. 2;

FIG. 4 is a front elevational view of FIG. 2;

FIG. 5 is a rear elevational view of FIG. 2;

FIG. 6 is a right side elevational view of FIG. 2;

FIG. 7 is a left side elevational view of FIG. 2;

FIG. 8 is a perspective view of a second embodiment of the design shown in FIG. 1;

FIG. 9 is a top plan view of the media storage container of FIG. 8;

FIG. 10 is a bottom plan view of FIG. 9;

FIG. 11 is a front elevational view of FIG. 9;

FIG. 12 is a rear elevational view of FIG. 9;

FIG. 13 is a right side elevational view of FIG. 9; and,

FIG. 14 is a left side elevational view of FIG. 9.
